獨白 4

三

FIG. 1 is a perspective view of a portable water heater showing my new design;

FIG. 2 is a perspective view of the opposite side thereof;

FIG. 3 is a side elevational view thereof;

FIG. 4 is an elevational view taken from the right side of FIG. 3;

FIG. 5 is a bottom plan view thereof on an enlarged scale; and

FIG. 6 is a top plan view thereof.

The gas tank and clamp are shown in broken lines in FIGS. 4 and 6 for illustrative purposes only.

The mesh on the exhaust vent is partially shown in FIGS. 2 and 3 for convenience of illustration, it being understood that the mesh is continuous on the vent.

I claim:

An ornamental design for a portable water heater, as shown and described.
